(57) **CLAIM**

The ornamental design for combined spork, knife, and fire starter, as shown and described.

DESCRIPTION

FIG. 1 is a top perspective view of a combined spork, knife, and fire starter, showing my new design;

FIG. 2 is a front elevation view thereof;

FIG. 3 is a back elevation view thereof;

FIG. 4 is a first side elevation view thereof;

FIG. 5 is a second side elevation view thereof;

FIG. 6 is a top plan view thereof;

FIG. 7 is a bottom plan view thereof;

FIG. 8 is a top perspective view thereof, shown without the
knife and fire starter for ease of illustration;

FIG. 9 is a front elevation view thereof, shown without the
knife and fire starter for ease of illustration;

FIG. 10 is a back elevation view thereof, shown without the
knife and fire starter for ease of illustration;

FIG. 11 is a first side elevation view thereof, shown without
the knife and fire starter for ease of illustration;

FIG. 12 is a second side elevation view thereof, shown
without the knife and fire starter for ease of illustration;

FIG. 13 is a top plan view thereof, shown without the knife
and fire starter for ease of illustration

FIG. 14 is a bottom plan view thereof, shown without the
knife and fire starter for ease of illustration;

FIG. 15 is a top perspective view thereof, shown without the
spork and fire starter for ease of illustration;

FIG. 16 is a front elevation view thereof, shown without the
spork and fire starter for ease of illustration, shown in
enlarged scale;

(Continued)

FIG. 17 is a back elevation view thereof, shown without the spork and fire starter for ease of illustration, shown in enlarged scale;

FIG. 18 is a first side elevation view thereof, shown without the spork and fire starter for ease of illustration;

FIG. 19 is a second side elevation view thereof, shown without the spork and fire starter for ease of illustration;

FIG. 20 is a top plan view thereof, shown without the spork and fire starter for ease of illustration;

FIG. 21 is a bottom plan view thereof, shown without the spork and fire starter for ease of illustration;

FIG. 22 is a perspective view thereof, shown without the spork and knife for ease of illustration;

FIG. 23 is a front elevation view thereof, shown without the spork and knife for ease of illustration;

FIG. 24 is a back elevation view thereof, shown without the spork and knife for ease of illustration;

FIG. 25 is a first side elevation view thereof, shown without the spork and knife for ease of illustration;

FIG. 26 is a second side elevation view thereof, shown without the spork and knife for ease of illustration;

FIG. 27 is a top plan view thereof, shown without the spork and knife for ease of illustration;

FIG. 28 is a bottom plan view thereof, shown without the spork and knife for ease of illustration; and,

FIG. 29 is an exploded top perspective view thereof.

The broken lines shown in the figures indicate elements that do not form part of the claimed design.

The dot-dot-dash broken lines of FIG. 29 are included to show relationship of the spark to the knife and the fire starter only and forms no part of the claimed design.
